FOREIGN PATENT DOCUMENTS

WO D025679-001 * 5/1993

Primary Examiner — Catherine A Tuttle(74) *Attorney, Agent, or Firm* — Dickinson Wright PLLC;
Andrew D. Dorisio(57) **CLAIM**

The ornamental design for a spray cap for aerosol containers, as shown and described.

DESCRIPTION

FIG. 1 is a perspective top front perspective view showing my new design for a spray cap for aerosol containers, in a closed condition;

FIG. 2 is a top, back and left perspective view thereof;

FIG. 3 is a back view thereof;

FIG. 4 is a left side view thereof;

FIG. 5 is a front view thereof;

FIG. 6 is a right side view thereof;

FIG. 7 is a top view thereof;

FIG. 8 is a top front perspective view showing my new design, in an open condition;

FIG. 9 is a top, back and left perspective view thereof;

FIG. 10 is back view thereof;

FIG. 11 is a left side view thereof;

FIG. 12 is a front view thereof;

FIG. 13 is a right side view thereof; and,

FIG. 14 is a top view thereof.

The broken lines in FIGS. 7 and 14 depict interior details that form no part of the claimed design.

1 Claim, 14 Drawing Sheets(56)
